UNITED STATES PATENT OFFICE.

THOMAS NATHAN RUSSELL, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

CAR-ROOF.

1,255,231.

Specification of Letters Patent. Patented Feb. 5, 1918.

Application filed May 12, 1916. Serial No. 97,154.

To all whom it may concern:

Be it known that I, THOMAS NATHAN RUSSELL, a citizen of the United States, residing in Chicago, in the county of Cook and State of Illinois, have invented a new and useful Improvement in Car-Roofs, of which the following is a specification.

The invention relates to metal car roofs, and has for its principal object to provide 10 a weather-proofing joint for the eaves ends of the roof sheets, which allows freedom of movement of the parts during car-flexure, and is practically free from rubbing contact of the movable parts so as to prevent the 15 wearing of the galvanizing. Also to provide such a joint as will maintain the weather-proof integrity of the roof in case of certain injuries to the eaves of the car which would ordinarily cause leakage.

With such objects in view, the invention 20 consists in the parts and combinations thereof hereinafter set forth and claimed, and in such useful and advantageous features of construction as are incident to the improved 25 roof as herein illustrated.

In order to make the invention more clearly understood there are shown in the accompanying drawings means for carrying the same into practical effect, without limiting the improvements, in their useful applications, to the particular construction which, for the purpose of example, has been made the subject of illustration.

In the said drawings—

Figure 1 is a plan view of a portion of an outside metal car roof embodying the invention, the same being partly broken away.

Fig. 2 is a side view of a portion of the same, on a larger scale.

Fig. 3 is a sectional view, on a larger scale, on line III—III of Fig. 2.

Fig. 4 is a section on line IV—IV of Fig. 1.

Fig. 5 is a section on line V—V of Fig. 2.

Fig. 6 is a perspective view of the eaves end of one of the roof sheets.

Referring to the drawings, 1 indicates the side plates of the roof frame, 2 the carlines, 3 the ridge pole, 4 the purlins, and 5 the 50 top sheathing. 6 is the side sheathing and 7 the side fascia.

The roof sheets are shown at 8, preferably made of galvanized sheet iron. They are formed at one edge (Fig. 4) with an up-

standing underlapping side flange consisting of a substantially vertical part 9 which is bent over to form an inclined flange or lip 10 which overhangs the body of the roof sheet. At its other side the sheet is formed with an upstanding overlapping flange 60 which extends away from the body of its sheet and over the next sheet so as to inclose and movably interlock with the flange 9, 10. Said inclosing flange consists of a substantially vertical part 11 formed with a 65 relatively wide bend 12 at its top, and continued in the form of an outwardly inclined flange 12 terminating in an upwardly and inwardly turned tip 13. The inner flange parts 9 and 10 are embraced loosely within 70 the outer flange parts 11 and 12 of the next sheet, and the edge of the flange 10 engages between the tip 13 and the flange 12, the outer flange parts forming in effect a seam cap. 75

The roof sheets interlocked by such seam are movable relative to each other, within limits, both toward and from the eaves and in directions parallel therewith.

The ridge ends of the roof sheets are 80 formed with inverted U-bends 14 extending away from the body of the sheet, and the said bends of the contiguous sheets at opposite sides of the ridge are interlocked to form a ridge seam (Fig. 5) the parts of 85 which can telescope and yield to allow of said movements of the roof sheets. The intersections of the side and ridge seams are inclosed by caps 15 which are in turn inclosed by saddles 16, and said saddles and 90 caps are secured by bolts 17 which pass down through spaces between the ends of the bends 14 and through the top sheathing, ridge pole and top flanges of the car lines (Fig. 5). 95

The roof sheet side seams are loosely confined at their eaves ends by seam clips 18 comprising hoods 19 which inclose said ends of the seams, and leg or bracket portions 20 which are attached to the side of the car, 100 preferably upon the outer side of the fascia 7 (Fig. 3) and have substantially horizontal shoulders 21 which rest on the fascia or on the eaves flashing hereinafter described, the hood of the seam clip having a 105 substantially vertical end wall 22.

Between its said upstanding side flanges the eaves edge of each roof sheet is turned

under to form a hook flange 24 which engages beneath the outwardly extending hook 25 of a hooked eaves strip 26. The lower flange 27 of said eaves strip is secured to the 5 side of the car, preferably between the fascia and side sheathing (Fig. 3). It will be understood that the hook flanges 25 extend substantially continuously from end to end of the car, and the hook flanges 24 similarly 10 extend, excepting that they are ordinarily interrupted for short spaces at the side seams of the roof sheets. 28 is an eaves flashing which extends over the fascia, beneath the hook flanges 24 and into the space 15 beneath the hook flanges 25, thereby protecting the fascia and upper parts of the side sheathing from deterioration. This flashing prevents any leakage into the wooden parts of the car along the eaves strip flanges 27.

20 The said eaves strips are formed with vertical flanges 29 which depend along the outer sides of the fascia and are received in seats 30 formed for the same in the inner face of the legs 20 of the seam clips.

25 Furthermore, the inner portions of the roof sheet hook flanges 24 are extended upward as shown at 31, preferably substantially to the flanges 25 of the hook strips, being thereby kept out of contact with the 30 flashing 28 so as to prevent the working of water inward by capillary action between the said parts 28 and 31, and also acting as obstructions against the dashing of water outward between the parts 31 and 25. The 35 inner edge of the flashing 28 terminates in an upstanding flange 32 extending longitudinally of the car, which prevents rain-water which may penetrate this eaves seam from passing outward and downward between the 40 flashing and the hook strip. The above described construction of the eaves seam of the roof sheets allows of limited movements of the sheets longitudinally of the car and in any other direction.

45 The said construction of the eaves seam gives it considerable depth, and the top sheathing is preferably entirely removed to accommodate the seam, terminating it about the outer edge of the side plate. The joint 50 between the side plate and side sheathing which is thus left uncovered is protected by the hook strip 26.

The large radius at the bend of the hook flange 24 prevents the fracture of the galvanizing on the sheet. The hook on the end of the sheet being turned up at its lower end, prevents the sheet from flapping in the wind and holds the sheet down on the top of the hook-strip 26. There is a clearance between 55 the underside of the outer end of the sheet and the eaves flashing 28, which prevents chafing of the galvanizing on the sheet. There will possibly be a little friction or 60 chafing at the inner end of the hook flange 24 on the sheet where it engages the hook-

strip, but this is of no consequence as it is in a dry place protected from the weather. The inner end of the eaves-flashing being curved upwardly, prevents water from seeping in under the sheet and passing down behind the fascia. 70

The present invention relates broadly to and is an improvement on the hook-strip construction arranged inside of the outside clearance line of the car, and shown in the 75 patent to Mathews, No. 782,979, dated February 21, 1905; and in my Patent No. 1,173,220, dated February 29, 1916; and in my pending application Serial No. 822,258, filed March 4, 1914; and in many respects 80 not inconsistent with the construction described in this present application, the roof is or may be similar to the roofs described in said patents and pending application.

What is claimed is:

1. In a metal car roof, in combination: a car roof frame; roof sheets movable within limits on said frame and formed at their eaves ends at points over the car frame with relatively large downward and inward 90 bends of more than a semi-circle, from which bends the terminal portions of the sheets extend inward and upward under the body of the sheet and at an angle thereto; and hook strips under the roof sheets attached to the car frame and having hook flanges extending outward over and confining the terminal edges of the sheets. 95

2. A roof sheet for car roofs, formed at its eaves end with a relatively large downward and inward bend of more than a semi-circle, 100 from which bend the terminal portion of the sheet extends inward and upward under the body of the sheet and at an angle thereto, and terminates in an upwardly and inwardly inclined flange near the under surface of the sheet. 105

3. In a metal car roof, in combination: a car roof frame; roof sheets movable within limits on said frame and formed at their 110 eaves edges with hook flanges which are bent upward toward the under sides of the roof sheets; hook strips attached to the car frame and having hook flanges extending outward over the said flanges of the roof sheets; and 115 eaves flashings independent of the hook strips, covering the fascia and extending inward between the roof sheet hook flanges and the hook strips, and formed with upstanding inner edges adapted to turn back water and 120 to be drawn out from the hook seam in case of injury to the flashing.

4. In a metal car roof, in combination: a car roof frame; roof sheets movable within limits on said frame and formed at their 125 eaves edges with undeturned hook flanges; hook strips attached to the car frame and having hook flanges extending outward over the said flanges of the roof sheets; and eaves flashings independent of the hook strips, 130

covering the fascia and extending inward between the roof sheet hook flanges and the hook strips, and formed with upstanding inner edges adapted to turn back water and 5 to be drawn out from the hook seam in case of injury to the flashing.

In testimony whereof I have hereunto set

my hand in the presence of two subscribing witnesses.

THOMAS NATHAN RUSSELL.
